A. M. PURCHIO

CONTROLLING MECHANISM FOR HEADLIGHTS

Filed Aug. 5, 1926

Patented June 5, 1928.

UNITED STATES PATENT OFFICE.

AMICO MICHAEL PURCHIO, OF BUFFALO, NEW YORK.

CONTROLLING MECHANISM FOR HEADLIGHTS.

Application filed August 5, 1926. Serial No. 127,330.

This invention relates to a controlling mechanism whereby the stream of light issuing from an automobile head-light or lamp may be controlled so as to avoid a blinding glare in the eyes of on-coming persons.

It is the object of this invention to provide a mechanism of this character which can be readily applied to cars of standard construction, which can be readily operated from the driver's seat to suit different road conditions, and which can be readily adjusted so as to either increase or decrease the amount of light emitted from the head-light or lamp in accordance with the rules or regulations in any particular locality.

In the accompanying drawings:

Figure 1 is a fragmentary perspective view of an automobile equipped with my improved light controlling mechanism.

Figure 2 is a fragmentary horizontal section of the light controlling mechanism embodying my invention.

Figure 3 is a front elevation of a head-lamp equipped with one form of shutter and associated parts in accordance with my improvements.

Figure 4 is a fragmentary front elevation, partly in section, of the means for adjustably connecting a shutter with its operating shaft.

Figure 5 is an elevation, partly in section, of the mechanism for retaining the hand lever in its adjusted position.

Figure 6 is a perspective view of part of the locking means for adjusting the position of the shutter on its operating shaft.

Figure 7 is a fragmentary plan view showing a modification of the means for adjustably connecting the shutter with its operating shaft.

Similar characters of reference indicate like parts in the several figures of the drawings.

My invention is applicable to automobiles or motor cars of standard construction, that shown in the drawings consisting of a main frame 10, an engine 11 mounted on the front part of the frame, a radiator 12 arranged in front of the engine, and two head-lights or lamps 13, 13 mounted on the front part of the frame on opposite sides of the radiator.

The preferred embodiment of my invention shown in Figs. 1-6, is constructed as follows:

Arranged in front of each head-light is a shutter 14 which is capable of moving in a

vertical plane at right angles to the lamp with which the same is associated. Along the inner side of each head-light is arranged the horizontal longitudinal operating shaft 60 15 for the shutter of the respective lamp. This shaft is adapted to be rocked back and forth through a definite predetermined arc by an operating mechanism which is within convenient reach of the driver while occupying his usual seat in rear of the engine, which rocking motion is imparted to the shutter so as to either uncover the respective lamp when driving on a roadway while no one is approaching from the opposite direction, or 70 covering the lamp more or less when some one is facing or approaching on the roadway from the opposite direction. By this means the road ahead may be either fully and brilliantly illuminated at night when no persons are present who would be blinded or dazed by the glare of the head-lamps, but also rendering it possible to cut down or obstruct so much of the stream of light issuing from the head-lamp that no glaring effect is 80 produced by the same on the eyes of on-coming persons. For this reason, the shutter operating mechanism is so designed that in the normal operative position of the shutter, the same is arranged in front of the upper 85 part of the respective lamp, but in the in-operative position of the same it is moved upwardly above the lamp.

The laws of different localities vary as to the stream of light which may be thrown 90 forwardly from the lamp and means are therefore provided for varying the extent of downward movement of the shutter across the upper front part of the head-lamp to meet the requirements of local regulations. 95 Although various means may be provided for this purpose, those shown for example in Figs. 1-6 are constructed as follows:

The numeral 16 represents a hub or collar secured to the front part of the respective operating shaft and engaging with the rear side of the shutter at that end thereof through which the operating shaft passes. The front end of the operating shaft is 100 screw threaded and receives a clamping screw 105 nut 17 which engages with the front side of the shutter. On one side of the axis of the operating shaft the shutter is provided with a curved slot 18 which is concentric with the axis and provided on one or both, 110 preferably both edges with rows of serrations or teeth 19 which are adapted to re-

ceive the teeth 20 formed on one or both sides of a locking block 21 movably mounted on the hub 16. In the preferred construction this locking block is arranged on the intermediate part of an adjusting bolt 22 which latter passes through the curved slot 18 of the shutter and the adjacent part of the hub 16 and is provided with a rear clamping screw nut 23 engaging the rear side of the hub 16 and a front clamping screw nut 24 engaging with the front side of the shutter.

When it is desired to adjust the shutter on the operating shaft for cutting off more or less of the stream of light from the lamp to suit a certain local requirement, then the rear screw nut 23 is first loosened and the clamping bolt 22 pushed forwardly sufficiently to disengage the locking block 21 from the serrations of the shutter after which the latter may be shifted circumferentially to the position desired relatively to the operating shaft. Thereafter the locking block 21 is again moved rearwardly into engagement with different locking notches or serrations and then held in place by tightening the rear screw nut 23. Upon now operating the shutter from the driver's seat, the same will swing through the same arc but the extent which the same in its operative position covers the lamp and the stream of light issuing therefrom will be changed in accordance with the changed relative position of the shutter and operating shaft, thereby enabling this shutter operating mechanism to be readily adapted to meet local requirements.

For convenience in locating the lower edge of the shutter with reference to the extent of its closure position over the front of the head-light, the free end of the shutter is provided on its front side with a row of graduations which may be numbered as shown at 25, or otherwise designated so as to enable the operator by bringing one or the other of these graduations into a horizontal position relative to the operating shaft, it is possible to fix the shutter in a predetermined position on this shaft so that when the shutter is moved fully into its operative position, its lower edge will go down across the lamp the requisite extent to suit the law.

Each of the longitudinal operating shafts 55 extends through a casing 26 mounted on the adjacent part of the automobile, which casing is provided in its front wall with a front bearing 27 in which the operating shaft is journaled immediately in rear of the hub 16, while the rear end of this shaft is journaled in a rear bearing 28 in the rear wall of this casing. The opposing side walls of both casings are provided with bearings 29, 29 in which are journaled the two stub or end sections 30, 30 of a transverse shaft, which lat-

ter has an intermediate section 31 detachably connected with said stub sections by providing the opposing ends of the intermediate and stub sections with interengaging tongues 32, and recesses 33, and bolts 34 passing through said tongues and recessed parts.

Within each casing is arranged a pair of intermeshing bevel gear wheels 35, 36 which are secured respectively to the longitudinal operating shaft and the transverse stub shaft. In order to ensure a tight fit of the parts in the casing and prevent rattling, a spring washer 37 is mounted on the operating shaft between the bevel gear wheel 35 thereon, and the front wall of the casing, and a similar spring washer 38 is interposed between the bevel gear wheel 36 and the side wall of the casing, as best shown in Fig. 2.

A rocking motion is imparted to the transverse shaft by a hand lever 40 arranged adjacent to the driver's seat, through the medium of intermediate transmitting mechanism. This lever is pivoted to swing vertically on a bracket 39 which is secured to the instrument board or other part of the car, and has upper and lower arms. At a point between the head-lights and the driver's seat, a vertically swinging intermediate lever 41 is provided, the same being pivoted on a bracket 42 secured to the adjacent part of the main frame. The lower arm of this intermediate lever is connected by a front rod 43 with a rock arm 44 depending from the intermediate section of the transverse shaft, and a rear rod 45 connecting the upper arm of the intermediate lever with the lower arm of the hand lever. Upon swinging this hand lever back and forth, the shutters of both head-lights will be simultaneously raised and lowered. In order to permit of holding the shutters and the parts associated therewith in either extremes of their throw, a locking device is provided which in its preferred form, as shown in Figs. 1 and 5 comprises a projection 46 having the form of a roller arranged on the upper arm of the hand lever, a curved latch 47 having its concave side facing the projection and provided near its ends with notches 48, 49, a pivot connecting one end of this latch with the bracket 39, a stop 50 arranged on this bracket and adapted to be engaged by the inner side of the opposite end of the latch, and a spring 51 connecting said latch with said bracket 120 and operating to hold the latch yieldingly in engagement with said stop. When the hand lever is in either extremes of its movement, the projection 46 of the same engages with one or the other of the notches 48, 49 of the latch and is yieldingly held thereby in this position. When it is desired to shift the shutters, sufficient pressure must be applied to the hand lever to overcome the tension of the spring 51 after which the completion of 130

the stroke of the hand lever can be effected with ease and facility, and when the end of the stroke is reached, the projection 46 engages the other notch of the latch for holding the parts impassively in this changed position.

The shutters can by this means be quickly raised into their elevated inoperative position, as shown by dotted lines in Fig. 1, for 10 night driving on a clear road ahead, or the shutters can be lowered so as to cover the upper parts of the lamps, as shown by full lines in the same figure, and thereby cut off the glaring effect of the lamps from on- 15 coming traffic during night driving whenever this is necessary to prevent accidents, due to glaring lights striking the eyes of persons on the road ahead.

For convenience in accurately adjusting 20 the intermediate mechanism which transmits motion from the hand lever to the shutters one of the connecting rods, for example the rear one, as shown in Fig. 1, is constructed of sections which have right and left hand- 25 screw threads 52, 53 and these are engaged by a turn buckle 54 correspondingly threaded. By turning this buckle 54 the transmitting mechanism can be adjusted so that the shutters are in their correct operative 30 position when the hand lever is at one extremity of its throw.

If desired, the adjustment of each shutter

relative to its operating shaft may be effected by providing the shutter around the shaft 15 with an annular row of serrations 55 and 35 engaging the same with a similar row of serrations 56 on the hub 16, these serrations after adjustment being held in locking engagement with each other by tightening the nut 57 arranged on operating shaft and bearing 40 against the front side of the shutters as shown in Fig. 7.

I claim:

A controlling mechanism for head lights comprising a shutter adapted to move vertically in front of the light in a plane at right angles to the axis thereof, a longitudinal shaft adapted to be arranged on one side of the light, and means for adjustably mounting said shutter on said shaft, comprising a hub 50 secured to said shaft, a clamping nut on said shaft adapted to press said shutter against said hub, said shutter being provided with a slot which is concentric with said shaft and having serrations on its edge and a clamping 55 bolt passing through said slot and adapted to draw the shutter and hub together and provided with a locking block arranged in said slot and provided with a tooth adapted to engage with one or another of said serrations.

In testimony whereof he hereby affixes his signature.

AMICO MICHAEL PURCHIO.
